GOLF RAKE

Filed April 24, 1936

UNITED STATES PATENT OFFICE

2,110,538

GOLF RAKE

William J. Walsh, Oak Park, Ill.

Application April 24, 1936, Serial No. 76,092

3 Claims. (Cl. 55—10)

One of the objects of the present invention is to provide a novel, improved and compact golf rake which is adapted to be collapsed or folded so as to occupy a minimum space and when so collapsed can be conveniently carried in the golf bag of a golfer so that when the same is unfolded and extended it can be used for retrieving golf balls from water hazards or for leveling off sand traps.

Another important object of the invention is to provide a novel and improved form of a collapsible golf rake in which the teeth thereof are adapted to be folded so as to occupy a contiguous position with respect to the handle and in addition thereto is provided with a telescopically extensible handle for extending the length thereof.

These and other objects are accomplished by providing an arrangement of the various parts in the manner hereinafter described and particularly pointed out in the appended claims.

Referring to the drawing:

Fig. 1 is a perspective view of my improved golf rake;

Fig. 2 is a cross sectional view taken on the line 2—2 in Fig. 1;

Fig. 3 is a cross sectional view taken on the line 3—3 in Fig. 2 showing the manner in which all of the teeth may be folded in dotted line position with respect to the handle;

Fig. 4 is an enlarged fragmentary view showing the manner in which all the teeth of the rake as well as the pivoted sections thereof are collapsed or folded in compact form so as to assume a position substantially parallel to the main section of the handle;

Fig. 5 is a fragmentary detailed view partly in cross section illustrating the construction of the telescoping handle; and

Fig. 6 is an enlarged fragmentary top plan view of the center rake section.

In illustrating one form of my invention I have shown the same as comprising a center or main raking section, generally indicated by the reference character 10. Pivotedly connected to the main or center section 10 by means of bolts 11 are outer or supplemental raking sections 12. The main section 10 comprises a prism-like center block 10' to the opposite sides of which are secured, by means of rivets 13, rectangular plates 11'.

Secured against the opposite ends of the block 10' by means of the bolts 11 are rectangular blocks 14 to which are rigidly secured the inner rake teeth 15. Pivotedly secured by means of

pins or bolts 16 to each of the sections 12 are similar rectangular blocks 17. Rigidly secured to each of these blocks adjacent each of the inner edges thereof are rake teeth 18. Pivotedly connected to each of the blocks 17 on each of the sections 12 are connecting bars 19 by means of bolts 20. The inner ends of each of these bars 19 are pivotally connected by means of bolts 21 to the fixed blocks 14 as clearly shown in Figs. 2 and 4 of the drawing. Obviously upon an actuation of each of the sections 12 about their pivots 11 on the main section 10 they will occupy a position substantially parallel to each other as clearly shown in Fig. 4 of the drawing. Secured to the center block 10' by a stud 21' and a rivet 22' is a bracket 22 which is pivotally secured by means of a bolt 23 to a main tubular handle section 24. Secured to the upper end of the main handle section 24 is a sleeve 25 which is provided with an internal annular flange 26 which is adapted to engage an external annular flange 27 formed on the inner end of a telescoping shaft 28 which is telescopically mounted within the main or tubular shaft 24 as clearly shown in Figs. 1 and 5 of the drawing. The upper end of the shaft 26 is provided with a handle 29. Adjacent the inner end of the handle 29 is a threaded section as shown at 30 which in turn is adapted to engage the internal threaded portion 31 of the sleeve 25 for securing the extension in compact or collapsed form as shown in the full line in Fig. 1 of the drawing. If the operator is desirous of extending the length of the handle, these sections are unscrewed from one another and extended as shown in the dotted line position of Fig. 1.

Summarizing the operation of my improved golf rake, let us assume that the rake is in the operative or extended position shown in dotted lines in Fig. 1. When in this position the handle may be collapsed in the manner previously described by telescopically sliding the extended handle portion into the main or tubular section 24 and secured in position by screwing the threaded portion 30 into the threaded portion 31 of the sleeve 25. The rake head may be folded by actuating the sections 12 about their respective pivots 13 on the main section 10 so as to assume the position shown in Fig. 4, after which, the main section may be actuated about its pivot 23 from the full line position shown in Fig. 3 to the dotted line position shown in the same figure so that the sections 12 as well as the teeth of the rake extend in substantial parallelism with the tubular section of the handle. The rake

head assumes a compact form so that a bag may be placed around the collapsed rake sections and the golf rake inserted in the golf bag of the golfer.

5 From the above description it will be readily seen that I have not only provided a simple, compact and easily manipulated golf rake and one which assumes little more, if any, space than an ordinary golf club so that the same may be 10 conveniently carried by a golfer for retrieving his golf balls from water hazards or for raking the sand traps of the golf course.

While in the above specification I have described one embodiment which my invention may 15 assume in practice, it will, of course, be understood that the same is capable of modification and that modification may be made without departing from the spirit and scope of the invention as expressed in the following claims.

20 What I claim is my invention and desire to secure by Letters Patent is:

1. A golf rake comprising a telescoping handle, a main rake section having relatively stationary teeth, pivoted to said handle, and supplemental sections pivoted to said main section 25

and having a plurality of pivoted teeth, pivoted to the outer end of said main section.

2. A golf rake comprising a telescoping handle, a main section pivoted to said handle and foldable with respect thereto, rake teeth secured to said main section, outer rake sections pivoted to and adapted to be folded with respect to said main section, and pivoted teeth carried by said outer sections and adapted to be folded in parallelism with respect to said handle. 10

3. A golf rake comprising a tubular handle, a telescoping extension mounted in said tubular handle, a main rake section pivoted to one end of said tubular handle, spaced apart teeth fixed to said main section, supplemental outer sections pivoted to said main section, pivoted teeth mounted on each of said outer sections, bars operatively connecting all of said pivoted teeth with said main section whereby said outer sections may be folded with respect to said main section 15 and said main section folded with respect to said tubular handle for extending said section and said teeth in parallelism with said handle. 20
